UNITED STATES PATENT OFFICE.

WILLIAM C. RAMSTEIN, OF LOS ANGELES, CALIFORNIA.

DESIGN FOR A FINGER-RING.

58,820.

Specification for Design.

Patented Aug. 30, 1921.

Application filed December 15, 1920. Serial No. 430,980. Term of patent 3½ years.

To all whom it may concern:

Be it known that I, WILLIAM C. RAMSTEIN, a citizen of the United States of America, residing at the city of Los Angeles, in the county of Los Angeles and State of California, have invented a new, original, and ornamental Design for Finger-Rings, of which the following is the specification, reference being had to the accompanying drawing, forming a part thereof.

Figure 1 is a front view of the finger ring.

Fig. 2 is a detail in section as seen on the line 2—2 of Fig. 1.

The design consists essentially in mounting an elk's tooth on the ring with an elk's head arranged adjacent thereto having the clock dial arranged in the antlers, as is common in the emblem of the Benevolent and Protective Order of Elks. The distinctive feature of the design resides in the arrangement and mounting of the several parts of the emblem on the ring, as shown.

I claim:

The ornamental design for a finger ring, as shown and described.

WILLIAM C. RAMSTEIN.
